UNITED STATES PATENT OFFICE.

DAVID E. HERRON, OF NEW PHILADELPHIA, OHIO.

MINER'S LAMP.

No. 804,659.

Specification of Letters Patent.

Patented Nov. 14, 1905.

Application filed June 6, 1905. Serial No. 263,923.

To all whom it may concern:

Be it known that I, DAVID E. HERRON, a citizen of the United States, and a resident of New Philadelphia, in the county of Tuscarawas and State of Ohio, have made certain new and useful Improvements in Miners' Lamps, of which the following is a specification.

My invention is an improvement in miners' lamps; and it consists in certain novel constructions and combinations of parts herein-after described and claimed.

Referring to the drawings forming a part hereof, Figure 1 is a perspective view of a miner's cap provided with my improved lamp. Fig. 2 is a rear perspective view of the support. Fig. 3 is a side view of the lamp and support, the latter in section; and Fig. 4 is a detail perspective view of the hook, showing the barb.

In the practical application of my invention I provide a lamp A of the form illustrated in Fig. 3 and a support B, comprising a plate of metal or other suitable material having a vertical portion a provided with a V-shaped opening a' and adapted to rest against the front of a cap A', an angular portion a² adapted to be secured to the peak of the cap, and an angular portion a³ adapted to be secured to the top of the cap and provided with a central opening a⁴, having a series of grooves a radiating therefrom.

A spring-catch a⁵, having the general form shown in Fig. 2, is arranged on the lower face 35 of the plate below the opening and comprises in the present instance a wire having a portion a⁶ secured to the plate, a portion a⁷ normally lying partially under the opening, and an arm a⁸ extending outwardly to the edge 40 of the plate and provided with a suitable push-button a⁹ on the end thereof.

A bracket B, comprising a hook b for engaging the opening a⁴ and a shank b', adapted to be secured to the lamp, is provided for 45 attaching the same to the support. The hook b is provided with a barb b² for engagement by the catch a⁵ to prevent withdrawal of the hook from the opening, and a lug b³ is arranged on the lower portion of the bracket 50 and is adapted to engage the V-shaped opening a' to prevent sidewise swinging of the lamp. On the right side of the lamp-body is provided a roughened or corrugated surface d for convenience in striking matches, 55 and beneath the angular portion of the support attached to the peak of the cap is an

opening a³, arranged to receive a lamp-picker a⁰.

The advantages of my invention will be readily understood from the description. 60 The lamp may be removed from the support for the purpose of cleaning or filling without removing the cap, since the grooves a⁷ will always guide the point of the hook into the opening. The V-shaped opening in the 65 front of the support assists likewise in this guiding movement. When engaged in the opening, the catch by engaging the barb prevents withdrawal of the hook, and the lug engaging the apex of the V-shaped opening prevents 70 sidewise movement of the lamp.

It is impossible to lose a lamp provided with my improvement, since the catch retains it firmly in place, thus removing a fruitful source of danger to the miner. The 75 miner's safety depends always upon his lamp and as a rule when it is most needed he is less in condition to pay attention to it. The double fastening of the lamp is of great convenience to the miner, since it gives him a 80 comparatively steady light of especial advantage in drilling.

It will be evident from the description that my device is simple in construction, inexpensive, easily operated, and not liable to get 85 out of order, and it is easily applied to the ordinary lamps and caps.

The lug will be detached from the V-shaped opening in undercutting to allow the lamp to hang perpendicularly, thus preventing 90 overflow of the oil.

Having thus described my invention, what I claim as new, and desire to secure by Letters Patent, is—

1. In combination, a miner's-lamp support, comprising a plate having a vertical portion to fit the front of the cap and provided with a V-shaped opening, an angular portion for attachment to the peak of the cap, and provided with a central opening and with a plurality of grooves radiating from the opening, a spring-catch below the opening, an arm for actuating the catch extending to the edge of the plate, a lamp-bracket comprising an upwardly-extending hook for 95 engaging the central opening and a barb for engagement by the catch, and a lug on the lower part of the bracket for engaging the V-shaped opening.

2. In combination, a lamp-support adapted to be secured to a cap and comprising a plate having a vertical portion provided with

- a V-shaped opening, and an angular portion provided with an opening and with grooves radiating from the opening, a spring-catch below the opening, a bracket adapted to be attached to the lamp and comprising a hook for engaging an opening in the angular portion of the support, a barb on the hook for engagement by the catch, a lug on the hook for engaging the V-shaped opening and means to release the catch.
3. In combination, a miner's - lamp support, adapted to be secured to a cap and comprising a plate having a vertical portion provided with a V-shaped opening, an angular portion provided with an opening and with grooves radiating from the opening, a bracket adapted to be attached to a lamp and comprising a hook for engaging the opening in the angular portion of the support, a barb on the hook, means below the opening for engaging the barb to prevent withdrawal of the hook, means for releasing said engaging means, and means on the hook for engaging the V-shaped opening.
4. In combination, a miner's - lamp support adapted to be secured to a cap, and comprising a plate having a vertical portion, and an angular portion provided with an opening and with grooves radiating from the opening, a bracket adapted to be attached to a lamp and comprising a hook for engaging the opening in the angular portion of the support, a barb on the hook, means below the opening for engaging the barb to prevent withdrawal of the hook, means for releasing the engaging means and means for preventing sidewise motion of the bracket, with respect to the support.
5. In combination, a miner's - lamp support, adapted to be secured to a cap and comprising a plate having a vertical portion, and an angular portion provided with an opening and with grooves radiating from the opening, a bracket adapted to be attached to

the lamp and comprising a hook for engaging the opening in the angular portion of the support, a barb on the hook, means for engaging the barb to prevent withdrawal of the hook, and means for releasing said engaging means.

6. In combination a miner's - lamp support adapted to be secured to a cap and comprising a plate having a vertical portion, and an angular portion provided with an opening and with grooves radiating from the opening, a bracket adapted to be attached to a lamp and comprising a hook for engaging the opening in the angular portion of the support, a barb on the hook means engaging the barb to prevent withdrawal of the hook from the opening and means for releasing the said engaging means.

7. In miners' lamps, the combination of a hook adapted to be attached to a lamp, a barb on the hook, a plate adapted to be attached to a cap and having an opening to receive the hook, means for engaging the barb to prevent withdrawal of the hook from the opening, and means to release said engaging means.

8. In miners' lamps, the combination of a hook, for attachment to a lamp, a barb on the hook, a support having an opening to receive the hook, means for guiding the hook to the opening and means engaging the barb for preventing withdrawal of the hook.

9. In miners' lamps, the combination of a hook for attachment to a lamp, a lug on the hook, a support having an opening to receive the hook and a seat to receive the lug, and means for guiding the hook and the lug into proper engagement with the opening and the seat.
